(57) CLAIM

The ornamental design for a pedicure spa, as shown and described.

DESCRIPTION

FIG. 1 is a front perspective view of a pedicure spa showing our new design;

FIG. 2 is a front view of the pedicure spa;

FIG. 3 is a rear view of the pedicure spa;

FIG. 4 is a right side view of the pedicure spa;

FIG. 5 is a left side view of the pedicure spa;

FIG. 6 is a top view of the pedicure spa; and,

FIG. 7 is a bottom view of the pedicure spa.

The broken lines immediately adjacent the shaded areas represent the bounds of the claim, while all other broken lines are directed to environment and are for illustrative purposes only; the broken lines form no part of the claimed design.

1 Claim, 3 Drawing Sheets

FIG. 1

FIG. 2

FIG. 3

FIG. 4FIG. 5

FIG. 6

FIG. 7
